Gardner Gilson, of Boston, Mass.

Letters Patent No. 2,150 - Dated Aug. 1, 1865.

Design for a Stove.

The schedule referred to in these Letters Patent and making part of the same.

To all Persons to whom these Presents shall come:

Be it known that I, Gardner Gilson, of Boston, of the County of Suffolk and State of Massachusetts, have invented or produced a frame its centre diverge rays A, B, C, like those of the sun, extending above, and to the right and left of it.

In the angle formed by the crossing of the compasses and square, and between it and the "cable tow" D, and on the left of the frame, there is represented a reclining lamb E, and in a similar space on the other side there is an hour glass F, and a scythe G. Extending up from the gauge D, on the left of the frame is a sword H, which crosses the compasses and square, and at the point where they cross and over the junction is placed a heart I. On the opposite side there is a gavel J, its handle resting upon the square.

On the lower half of the frame, on the right hand side thereof, there is a branch of laurel K, whilst on the other side there is a branch of oak L, the stems of these are tied together with a knot at the extreme lower part of the frame.

In the foreground and resting upon the square, and just below the "cable tow" D, there is an open Bible M, and on this is placed an open pair of compasses A and a square B, (in a similar position, relatively to each other as the compasses, and square B) and on the whole is laid a towel N.

This design is in taste appropriate, and all of the devices are symbols of the masonic order, except, perhaps, the cornucopia signifying industry, the laurel, beauty and purity and the oak, strength, which are used to "fill" the design.

2

What we claim as original with us, and desire to secure by Letters Patent is

The within described design for a masonic picture frame, substantially as herein shown and described.
